Have & Howell
ATTORNEY.

UNITED STATES PATENT OFFICE.

JOHN W. BLOODHART, OF DUBUQUE, IOWA, ASSIGNOR TO MIDLAND CHEMICAL LABORATORIES, INC., OF DUBUQUE, IOWA.

DESIGN FOR A LIQUID-SOAP DISPENSER.

Application filed June 27, 1927. Serial No. 22,573. Term of patent 14 years.

To all whom it may concern:

Be it known that I, JOHN W. BLOODHART, a citizen of the United States, residing at Dubuque, in the county of Dubuque and State of Iowa, have invented a new, original, and ornamental Design for a Liquid-Soap Dispenser, of which the following is a specification, reference being had to the accompanying drawing, forming part thereof.

The figure is a front elevation view of a liquid soap dispenser, showing my new design.

I claim:

The ornamental design for a liquid soap dispenser, as shown.

JOHN W. BLOODHART.
